(57) CLAIM

The ornamental design for a sleeveless shirt, as shown and described.

DESCRIPTION

FIG. 1 is a perspective view of a sleeveless shirt showing my new design;

FIG. 2 is a front elevational view thereof;

FIG. 3 is a left side elevational view thereof; and,

FIG. 4 is a rear elevational view thereof.

The labels and wording are shown in broken lines in FIGS. 1-4 for illustrative purposes only as the labels and wording form no part of the claimed design.

1 Claim, 4 Drawing Sheets
